CLAIM

The ornamental design for a bottle, as shown and described.

DESCRIPTION

FIG. 1 is a perspective view of a first embodiment of a bottle embodying the new design;

FIG. 2 is a front elevational view of the bottle of FIG. 1 (the back being identical therewith);

FIG. 3 is a side elevational view of the bottle of FIG. 2 (both sides being identical).

FIG. 4 is a top plan view of the bottle of FIG. 2;

FIG. 5 is a bottom plan view of the bottle of FIG. 2;

FIG. 6 is a front elevational view of a second embodiment of the bottle embodying the new design (the back being identical therewith);

FIG. 7 is a side elevational view of the bottle of FIG. 6 (both sides being identical);

FIG. 8 is a top plan view of the bottle of FIG. 6; and,

FIG. 9 is a bottom plan view of the bottle of FIG. 6.

The broken lines showing a bottle neck are for illustrative purposes only and do not form part of the claimed design.
